UNITED STATES PATENT OFFICE.

ALFRED BRANDRIFF, OF MILLVILLE, NEW JERSEY.

MACHINE FOR EDGING AND SEAMING PLATES.

SPECIFICATION forming part of Letters Patent No. 393,204, dated November 20, 1888.

Application filed March 8, 1887. Serial No. 230,154. (No model.)

To all whom it may concern:

Be it known that I, ALFRED BRANDRIFF, a citizen of the United States, residing at Millville, in the county of Cumberland, State of New Jersey, have invented a new and useful Improvement in Machines for Edging and Seaming Plates, which improvement is fully set forth in the following specification and accompanying drawings.

10 My invention consists of a machine for edging and seaming metal plates, embodying means for bending the plates, joining the same and rolling them on a reel or drum, and other features, as will be hereinafter fully set forth.

15 Figure 1 represents a side elevation of a machine for edging plates embodying my invention. Fig. 2 represents a top or plan view thereof. Figs. 3 and 4 represent vertical sections of the seam-closing mechanism thereof on lines *xx* and *yy*, respectively, Fig. 2. Figs. 20 5 and 6 represent transverse sections of the mechanism employed for throwing the rolling device in and out of gear on line *zz*, Fig. 2. Fig. 7 represents a transverse section of the 25 straightening device on line *aa*, Fig. 2. Figs. 8 and 9 represent partial side elevations and partial vertical sections of the bending or edging mechanism on an enlarged scale. Fig. 10 represents a vertical section of the adjusting 30 device of the bending or edging mechanism. Fig. 11 represents a top or plan view of the bending or edging blade and horizontal section of the studs, pins, or shoulders with which said blade engages, the parts being on a reduced scale.

35 Similar letters of reference indicate corresponding parts in the several figures.

Referring to the drawings, A represents the frame of the machine, the same having mounted on it the driving-shaft 1, which carries the 40 crank 2, whereby, by means of the treadle 3, power is communicated to said shaft 1. Geared with the shaft 1 is a shaft, 4, to which is secured the cam 5, which is adapted to bear 45 against an arm, 6, the latter being mounted on the frame A, and carrying at its outer end a blade, 7, whose sides have recesses 8, as will be seen in Fig. 11.

50 At the top of the frame of the machine is mounted a roller, 9, and above said roller is a head, 10, which is pivoted or hinged to the frame and rises and falls to a limited extent.

To the frame are attached catches 11, which rest over the ends of the side pieces, 12, of the head 10, opposite to the axis thereof, whereby 5 said head is prevented from rising. By turning the catches on their fastenings—pins or screws—they clear the side pieces, 12, and permit the head to be raised, whereby the roller 9 and adjacent parts of the machine are accessible for purposes requiring the same.

Beneath the head 10 is abutment 13, which is slotted and screwed to a block, 14, on the frame by means of a screw, 15, which passes through the slot of the abutment and enters 6 said block 14, said abutment, as is evident, being vertically adjustable. Secured to the under side of the head 10 are pins or studs 16, which are adapted to be engaged by the walls of the recesses 8 of the blade 7. Below the 7 roller 9 is a table, 17, above which is a weighted or gravitating arm, 18, whose lower end approaches said table, the upper end of said arm having a handle, 19, which is accessible at the side or top of the frame, whereby 7: the arm may be readily raised as desired. As will be seen in Fig. 8, the arm permits two contiguous sheets or plates of metal to pass under the same, but prevents more than that number from passing, it acting as a sweeper 8: or clearer for that purpose, as is evident.

It will be seen that as the shaft rotates the cam 5 bears against the arm 6 and raises the same, causing the blade 7 to enter between the head 10 and the face 20 at the top of the 8: block 14.

Mounted on the frame A is a shaft, 21, which is operated by the shaft 1 by means of intermediate gearing, and carries a drum, 22, and a gear-wheel, 23, the latter meshing with a pinion, 24, which is mounted on the frame A, and has loosely fitted on its axis an elbow, 25, the latter forming the bearing for a shaft, 26, which carries a gear-wheel, 27, having its periphery adjacent to the periphery of a gear-wheel, 28, the latter being secured to the shaft 29, which is mounted on the frame A and carries the reels or drums 30, on which the plates as edged are wound or rolled.

Rising from the table A are guides 31 for vertical sliding boxes 32, in which is journaled the depending segmental arm 33, whose peripheral face 34, when in normal position, is above and in advance of the periphery of the

roller 22. (See Fig. 3.) Connected with one of the journals, *a*, of the arm 33 is an arm, 35, from which depends a weight, 36, the rod 37, which is connected with said arm 33 and the weight 36, having attached to it near its upper end a stop, 38, which is adapted to abut against an adjacent portion of the frame A, so as to limit the rising motion of the segmental arm 33. (See Fig. 1.) To the other journal, *a'*, of the arm 33 is secured a crank, 39, whereby said arm 33 may be readily operated by hand.

At the side of the receiving end of the table 17 is an elbow-lever, 40, the vertical limb of which passes through said table and projects above the same. (See Figs. 5 and 6.) The horizontal limb of said lever is pivotally connected with a lever, 41, which is mounted on the table A, and has one end carrying a weight, 42, whereby the lever 40 is held inclined in its normal position, as shown in Fig. 5. The lever 40 has connected with it a spring, 43, to assist the return motion thereof, and a handle, 44, for conveniently operating said lever.

In the table 17 are openings *b* to receive blocks 45, each of which may be connected by a strap or link, 46, (shown in dotted lines,) with the lever 40, thus adapting said lever to be operated with plates of different widths, as will be hereinafter more fully set forth. At the side of the discharge end of the table 17 is a gravitating elbow-finger, 47, whose upper limb passes through an opening, 48, in said table and projects above the same.

In the table 17 are other openings, 49, and the finger 47 may be removed in order to be mounted adjacent to either opening 49, so as to be operative therein, the object of said finger being to keep the plates straight and true as they move over the table to the winding reel or drum, the openings 49 permitting the finger 47 to adjust itself relatively to plates of different widths. The weighted lever 41 is connected by a link, 50, with the arm 25, whereby as the weighted end of said lever rises the wheel 27 also rises and is caused to mesh with the wheel 28, whereby motion may be imparted to the shaft 29, and consequently to the reels 30. The shaft 29 carries a ratchet, 51, with which engages a pawl, 52, mounted on the frame A, whereby reverse motion of the shaft, and consequently of the reels 30, is prevented, it being noticed that the shaft is removably mounted in its bearings on the frame A.

The sliding boxes 32 of the segmental arm 33 are held in position by means of screws 53, which are fitted to the cross-bars at the top of the guides 31 and bear against said head. Springs 54 bear upwardly against the boxes 32 to raise the same when released by the screws 53.

The operation is as follows: The machine is set in motion by means of the treadle 3 or any other suitable power, and a sheet or plate of metal introduced between the roller 9 and head 10, and carried by said roller until its front

edge strikes the shoulder formed by the abutment 13 and block 14, as will be seen in Fig. 8. The cam 5 now bears against the arm 6 and forces the blade 7 toward the under side of the plate, near the end thereof, in the direction of the arrows of said figure. This bends the end portion of the plate and forces the same between the under side of the pivotal end of the head 10 and the upper face of the face 20 of the block 14, thus forming a hook on the end of a plate, as is shown near the top of Fig. 9 and at the lower left-hand corner of Fig. 8.

When the blade first strikes the metal blank or plate and begins to bend the same, the walls of the recesses 8 at the sides of said blade come in contact with the pins or studs 16 on the head 10, and thus move the head downwardly on its axis, so that the head advances toward the blank resting on the blade 7 and firmly presses the same thereagainst. The cam 5 now leaves the arm 6, and the latter, owing to its weight, drops or lowers and leaves the hook portion of the plate, the head 10 then rising and widening the space occupied by the hooked end of the plate, this being due to the action of the spring *c*, which rests on the frame A and bears upwardly against said head, whereby binding of the hooked end of the plate between the head and face 20 is prevented. The plate is now removed and reversed and again introduced beneath the head and subjected to operations similar to those stated, the result being a plate edged or having on its end hooks bent in opposite directions. A number of plates are hooked together, placed on the table 17 and advanced on the latter to the reels 30, where the hook of the first plate is connected with hooks *d* on the inner peripheries of said reels. As a blank-plate is placed on the table 17, it is rested against a flange or shoulder on one side of the same and forced against the projecting end of the lever 40. This forces said end outward and lowers the horizontal limb thereof. This raises the arm 25, whereby the wheel 27 is carried to the wheel 28 and caused to mesh therewith, so that the reels are rotated and the plates are drawn along and wound on said reel, forming a roll of continuous plates. When the hooks of two connected plates reach the face of the segmental arm 33, they bear against the same (see Fig. 3) and advance said arm, said arm occupying a tangential position to the roller 22. The arm now assumes a radial position in relation to said roller, whereby the hooks of the two plates are squeezed and united, (see Fig. 4,) the plates then continuing their motion.

When the hooked portions of the plates clear the arm 33, the latter returns to its normal position, as in Fig. 3, due to the action of the weight 36. As the plates leave the roller 22, they are guided on the table 17 by means of a flange or shoulder on one side of the same and the finger 47, the latter moving or yielding as the edge of each plate rides on the same, thus exerting its pressure against said edge and causing the plate to move true, and thus be

fed uniformly to the reel. When the ends of a plate clear the lever 40, the latter is immediately controlled by the weighted lever, and said lever returns to its normal position.

- 5 The weighted end of the lever 41 descends, thus lowering the wheel 27 and disengaging it from the wheel 28, thus stopping the reeling or rolling operation. As soon, however, as another piece of hooked metal is attached to 10 the advancing plate, the lever 40 is thrown out and the lever 41 is again operated, whereby the reeling or rolling operation continues.

When a roll of sufficient size is produced, it may be bound by a strap, band, cord, &c., 15 and removed with the shaft 29 from the bearing of the latter, after which said roll is slipped off the reel endwise, and the latter with its shaft may then be restored, ready for the formation of another roll.

- 20 The upper face of the abutment 13 is preferably rounded, and the edge of the metal plate rides on the same as it turns during the bending action of the blade 7, thus preventing dropping and displacement of the plate.

25 Having thus described my invention, what I claim as new, and desire to secure by Letters Patent, is—

1. In a machine for edging and seaming metal plates, a block secured to the frame 30 and having an abutment, a head pivoted to the frame, and a bending-blade adapted to enter between said head and the abutment of said block for bending the end of the plate, said parts being combined substantially as 35 described.

2. In a machine for edging and seaming metal plates, a pivoted head having pins on its under face, a block with an abutment, and a bending-blade with recesses on the side 40 thereof, said parts being combined substantially as and for the purpose set forth.

3. In a machine for edging and seaming metal plates, the combination of a bearing-block, a head pivotally connected to the frame 45 of the machine, the roller 9, the adjustable abutment 13, and the bending-blade 7, substantially as and for the purpose set forth.

4. In a machine for edging and seaming plates, the block 14, with face 20, the adjustable abutment 13, connected to said block, the roller 9, the head 10, with pins 16, and the bending-blade 7, with recesses 8 on its sides, said parts being combined substantially as described.

55 5. In a machine for edging and seaming metal plates, a bearing-block with abutment, a pivoted head with pins on its under face, the catches 11, arm 6, carrying the bending-blade 7, the latter having the side recesses, 8, and 60 shaft 4, with cam 5 thereon, said parts being combined substantially as described.

6. In a machine for edging and seaming metal plates, a bearing-block with abutment, a bending-blade, a pivoted head, and the spring 65 e, said parts being combined substantially as and for the purpose set forth.

7. In a machine for edging and seaming

metal plates; the combination of the table 17, the pivoted weighted arm 18, the shaft 29, with the reels 30 thereon, and mechanism, substantially as described, for rotating said shaft 29.

8. In a machine for edging and seaming metal plates, the combination of the table 17, the pivoted weighted arm 18, the reels 30, 75 mounted on the shaft 29, the pivoted segmental arm 33, the roller 22, the peripheral face 34 of said arm 33 being normally in advance and above said roller 22, and means, substantially as described, for rotating said shaft 29, substantially as described.

9. In a machine for edging and seaming metal plates, the table 17, weighted arm 18, the roller 22, the guides 31, rising from frame A, the sliding boxes 32, the segmental arm 33, 85 journaled in said boxes and having peripheral face 34, and the shaft 29, with reels 30 thereon, said parts being combined substantially as and for the purpose set forth.

10. In a machine for edging and seaming metal plates, the table 17, the roller 22, the journaled segmental arm 33, with peripheral face 34, the shaft 29, with reels 30 thereon, arm 35 on journal a of arm 33, rod 37, with weight, the stop 38, and the frame A, said parts being 95 combined substantially as described.

11. In a machine for seaming and edging metal plates, the combination of a table with opening b, a roller, a pivoted segmental arm with a peripheral face normally above and in front of said roller, a shaft with reels thereon, the block 45, the elbow-lever 40, connected to the block by strap 46, the lever 41, pivoted to the frame A and having the weight 42, the pinion 24, mounted on the frame A, an elbow 10 loosely fitted on the axle of said pinion and forming a bearing for the shaft 26, and the gear-wheel 27, mounted on said shaft 26 and engaging with a gear-wheel on the reel-shaft and with pinion 24, said lever 41 being connected 110 with the said elbow by link 50, substantially as described.

12. In a machine for edging and seaming metal plates, the table with opening b, the block 45, the pivoted lever 40, connected by 11 the strap 46 to said block, the lever 41, with weight 42, the shaft 29, with reels and gear-wheel 28, the driving-gear wheel 23, the pinion 24, mounted on the frame A, the elbow 25, loosely mounted on the axle of pinion 24 and 12 forming a bearing for the shaft 26 and carrying gear-wheel 27, adapted to engage with gear-wheels 28 and pinion 24, the link 50, and the spring 43, connected with lever 40, said parts being combined substantially as described.

13. In a machine for edging and seaming metal plates, a roller, a pivoted arm with peripheral face normally above and in front of said roller, a shaft with reels, a driving-shaft, mechanism, substantially as described, intermediate of said reel-shaft and driving-shaft for communicating motion to said reel-shaft, a pivoted lever with weight connected with said intermediate mechanism, a table with an open-

ing, and a block inserted in said opening and connected by a strap to an elbow-lever pivoted to said table, said elbow-lever being connected to the unweighted end of said weighted lever, 5 said parts being combined substantially as described.

14. In a machine of the character stated, the squeezing-arm 33, the bearing or roller 22, and the weight 36, connected with said arm, combined substantially as described.

15. In a machine of the character stated, a reel having a gear-wheel on its shaft, in com-

bination with a wheel geared with the driving-shaft of the machine, a rising-and-falling arm carrying the second-named wheel, a pivoted lever connected with said arm, and a lever on the supporting-table of the machine connected with said pivoted lever and operated by the metal plate, substantially as described. 15
